(57) **CLAIM**

The ornamental design for an access floor panel as shown and described.

DESCRIPTION

FIG. 1 is a top perspective view of an access floor panel, showing the new design;

FIG. 2 is a front elevation view thereof, with the rear elevation view being a mirror image of the front elevation view;

FIG. 3 is a left side elevation view thereof, with the right side elevation view being a mirror image of the left side elevation view;

FIG. 4 is a top plan view thereof;

FIG. 5 is a bottom plan view thereof;

FIG. 6 is a bottom perspective view thereof;

FIG. 7 is a cross sectional view taken at reference line 7-7 of FIG. 6;

FIG. 8 is a cross sectional view taken at reference line 8-8 of FIG. 6;

FIG. 9 is a cross sectional view taken at reference line 9-9 of FIG. 6; and,

FIG. 10 is a cross sectional view taken at reference line 10-10 of FIG. 6.

1 Claim, 6 Drawing Sheets
